UNITED STATES PATENT OFFICE.

DAVID N. MORTON, OF MITCHELL, NEBRASKA.

WAGON-JACK AND WRENCH.

1,239,936.

Specification of Letters Patent. Patented Sept. 11, 1917.

Application filed August 23, 1916. Serial No. 116,504.

To all whom it may concern:

Be it known that I, DAVID N. MORTON, a citizen of the United States of America, residing at Mitchell, in the county of Scotts Bluff and State of Nebraska, have invented certain useful Improvements in Wagon-Jacks and Wrenches, of which the following is a specification, reference being had therein to the accompanying drawing.

10 This invention relates to improvements in wagon jacks and wrenches, one object of the invention being the provision of a tool of this character which combines both of these elements in a single and handy implement, and which may be readily placed in position for use as a wrench or a wagon jack, and which when not in use, may be readily attached to the vehicle, preferably to the rear of the swingle or doubletree.

20 A further object of this invention is the provision of a device of this character which is simple, durable and inexpensive in construction, and thoroughly efficient and practical in use.

25 In the accompanying drawings:

Figure 1 is a plan view of the complete device.

Fig. 2 is a side elevation thereof.

Fig. 3 is a section taken on line 3—3 of Fig. 1.

Fig. 4 is a cross section taken on line 4—4 of Fig. 1.

Figs. 5 and 6 are detail views of the wrench members.

35 Referring to the drawings, the numeral 10 designates the two carrying plates which are held substantially apart, yet riveted together, by means of the spacing blocks 11, each one of which is provided with the 40 threaded opening 12 for the reception of the rotatable feed screw 13 which is thus disposed between and longitudinally of the plates.

Integral with the screw 13 adjacent the 45 outer end thereof is a transversely formed sleeve 14, while detachably connected to the outer end of the screw is the swivel abutting member 15, which is adapted to engage the axle when the present device is used as a 50 jack.

As is apparent this member 15 is cup-like in form and has a depression 16 therein which receives the screw, the member being held in place by a nut 17 engageable on the

outer end of the screw and seated within 55 the depression.

It will thus be seen that by rotating the screw by means of the removable headed handle bar 18, the relative position of the cup-like abutting member 15 to the plates 60 10 will be changed, and consequently the axle raised or lowered.

As intimated, a wrench has been provided and in the present instance consists of a rigid jaw 19 held rigidly between the opposite ends of the plates 10 by means of fastening devices 20. A movable jaw 21 has an opening 22 therein for engaging the screw 13, this jaw being held rigid with the feed screw so as to be adjusted therewith by 65 means of washers 23 and nuts 24 the latter holding the washers against the inner faces of the movable jaw. A substantially U-shaped frame 25 is also provided for bracing the movable jaw and for facilitating the 70 guiding of the jaw during adjustment. The intermediate portion 26 of the frame is anchored at the rear edge of the movable jaw by a fastening device 27 while the side arms of the frame straddle the plates and have 75 their terminals anchored on the respective sides of the movable jaw by fastening devices 28, this arrangement being illustrated in Fig. 6.

It is thought in view of the above description that it is evident that the foregoing arrangement has provided means for receiving and adjusting tool elements, the device as described being capable for use as a wagon 80 jack or as a wrench.

It will be understood that the foregoing description and accompanying drawings comprehend only the general and preferred embodiment of this invention and that various minor changes in detail of construction, 90 proportion and arrangement of the parts may be made within the scope of the appended claim and without sacrificing any of the advantages of my invention.

What I claim as new is:—

In a device of the class described, in combination a pair of carrying plates, a jaw projecting between said plates at one end and being secured thereto, a spacing block secured between said plates at their opposite 105 ends, a slideable jaw mounted between said plates and having a non threaded bore, a screw-bolt threaded into said block and pro-

jecting revolubly in said bore, nuts engaging said screw-bolt and engaging opposite sides of said slidable jaw, a rigid bearing member formed on said screw-bolt and a 5 connecting member having one side secured to one end of said slidable jaw and engaging one edge of said plate, two parallel sides.

slidably straddling said carrying plates and formed with terminal lugs extending inwardly and forming shoulders engaging the 10 opposite edge of each of said plates.

In testimony whereof I affix my signature.

DAVID N. MORTON.

Copies of this patent may be obtained for five cents each, by addressing the "Commissioner of Patents, Washington, D. C."
